CLAIM

The ornamental design for a fence bracket, as shown
and described.

DESCRIPTION

FIG. 1 is a perspective view of a fence bracket showing
my new design.

FIG. 2 is a top plan view thereof.

FIG. 3 is a side elevational view thereof, the opposite
side being a mirror image thereof.

FIG. 4 is a front elevational view thereof.

FIG. 5 is a bottom plan view thereof.

FIG. 6 is a rear elevational view thereof.

FIG. 7 is a perspective view of a fence bracket showing
a modified form of my new design.

FIG. 8 is a top plan view of FIG. 7.

FIG. 9 is a side elevational view of FIG. 7, the opposite
side being a mirror image thereof.

FIG. 10 is a rear elevational view of FIG. 7;

FIG. 11 is a bottom plan view of FIG. 7;

FIG. 12 is a front elevational view of FIG. 7.

The broken line showing of a portion of a fence in
FIGS. 1 and 7 is for illustrative purposes only.
